UNITED STATES PATENT OFFICE.

WILLIAM SHAKESPEARE, JR., OF KALAMAZOO, MICHIGAN.

FISHING-REEL.

No. 820,609.

Specification of Letters Patent.

Patented May 15, 1906.

Application filed July 31, 1905. Serial No. 272,038.

To all whom it may concern:

Be it known that I, WILLIAM SHAKESPEARE, Jr., a citizen of the United States, residing at the city of Kalamazoo, county of Kalamazoo, State of Michigan, have invented certain new and useful Improvements in Fishing-Reels, of which the following is a specification.

This invention relates to improvements in fishing-reels. It relates particularly to the frame construction thereof.

The objects of this invention are, first, to provide an improved fishing-reel frame which may be very easily assembled or disassembled; second, to provide an improved fishing-reel frame which may be easily disassembled by an inexperienced person for the purpose of removing the reel-spool or affording access to the bearings and gear without liability of disarrangement of the parts.

Further objects and objects relating to structural details will definitely appear from the detailed description to follow.

I accomplish the objects of my invention by the devices and means described in the following specification.

The invention is clearly defined, and pointed out in the claims.

A structure embodying the features of my invention is clearly illustrated in the accompanying drawings, forming a part of this specification, in which—

Figure 1 is a plan view of a fishing-reel embodying the features of my invention. Fig. 2 is a cross-sectional view thereof, taken on a line corresponding to line 2 2 of Fig. 1. Fig. 3 is a detail view, partially in longitudinal section, taken on a line corresponding to line 3 3 of Fig. 2, showing the structural details of the coupling-pillars B' for securing or coupling the heads together. Fig. 4 is a detail view, partially in longitudinal section, showing structural details of the pillars B. Figs. 5, 6, 7, and 9 are detail views, partially in longitudinal section, showing modified forms of the coupling-pillars. Fig. 8 is a detail cross-sectional view taken on a line corresponding to line 8 8 of Fig. 7. Fig. 10 is a detail end elevation view of the structure shown in Fig. 9 looking from the right thereof.

In the drawings similar letters of reference refer to similar parts throughout the several views, and the sectional views are taken look-

ing in the direction of the little arrows at the ends of the section-lines.

55

Referring to the drawings, the reel-frame heads A A' are preferably made up of outer and inner metallic plates a a', respectively, and an intermediate ring a'', preferably of rubber, hard fiber, or similar equivalent material. This head structure is illustrated and described in my copending application, filed August 18, 1902, Serial No. 120,270, and while it is preferred by me in this relation other heads may be used with satisfactory 65 results. The head structure illustrated, however, possesses a number of advantages in this relation.

The plates a a' and the rings a'' are suitably perforated to receive the ends of the pillars B B'. The pillars B are shouldered to properly space the heads. The inner plates a' rest against the shoulders. The pillars B are tapped at one end to receive the screws b'', which secure the plates and ring 70 forming the head A' upon the pillars. These screws drawing the plates and ring against the shoulders of the pillars properly secure them together.

The plates and ring forming the head A 80 are removably arranged upon the other end of the pillars B, being merely slipped thereon, as clearly appears in Fig. 4.

The head A is detachably secured by means of the pillars B', which I have designated as "coupling-pillars." These coupling-pillars B' are preferably two in number and are arranged on opposite sides of the reel-frame and when in position coact with the pillars B, forming part of the reel-frame. 85

The pillars B' are rotatably secured to the head A' and are provided with threaded studs to engage the outer plates a of the head A, so that by simply turning them the head A is secured or released. They also serve as 95 means for securing the plates a a' and the ring a'' of the head A together.

The coupling-pillars are preferably formed with a headed section B''', which is threaded into the main section, the section B''' being 100 arranged through the head A'. This, however, is a mere matter of structural economy and convenience. The pillars B' are preferably suitably knurled for convenience in grasping, as is illustrated in Figs. 1 and 3 of 105 the drawings.

From the foregoing it is evident that the head A may be released from the pillars or secured thereon by simply turning the pillars B'. This obviates the use of separate screws for securing the parts together, resulting in a great saving in the cost of manufacture, as the number of parts is materially reduced. It also results in a saving of time in assembling. When thus arranged, the pillars serve as guides for the parts of the heads, so that it is impossible for an inexperienced person to assemble them in any except the proper way, which of course greatly lessens the liability of injury to the structure.

15 The head A or the outer plate a thereof may be very quickly released when it is desired to remove the spool for any reason, such as the removing of snarls or knots in the line or the like or for cleaning or lubricating 20 the mechanism. Other advantages will readily appear to those skilled in the art.

In the modification shown in Fig. 5 the coupling-pillar is made up of two sections C and C'. The section C is rotatably secured 25 to the head A' by means of a screw, as b'', which is tapped into the end thereof. The section C is threaded at each end, the outer end engaging the outer plate a and securing the parts of the head A together. The inner 30 end is tapped into the section C. In this construction the head A can be released while the parts thereof are securely retained together.

35 In the modified construction shown in Fig. 6 the coupling-pillar is made up of the sections D, D', and D'', the section D'' being a coupling for the sections D and D'. The sections D and D' are both provided with threaded studs to engage the heads of the reel. The coupling D'' is revolvably mounted on the section D and is internally threaded at its other 40 end to engage the section D', which is suitably threaded.

45 In the modification illustrated in Figs. 7 and 8 the coupling-pillar E is provided with head-engaging studs E' E'', similar to those of Fig. 6. The stud E'' is revolvably secured in the pillar E, and the stud E' is provided with an elongated head e, adapted to be engaged by the cross-rods e', as clearly appears 50 from the drawings. This structure has the advantage of being very quickly released.

55 In the modification shown in Figs. 9 and 10 the coupling-pillar F is secured to the head A' by means of a screw b'', which is tapped into the end thereof. The other end of the pillar F is provided with an elongated head f, which is adapted to be arranged through the slot f' in the head A. When the pillar is given a quarter-turn, the head is locked upon 60 the pillar. This structure also has the advantage of great speed in securing or releasing the parts.

While I have illustrated these several modifications, I am aware that there are a number

of others which I believe are embraced within 65 the scope of my invention. I have illustrated these modifications merely to indicate the scope thereof, and while I desire to claim the same specifically in the form preferred by me I also desire to be understood as claiming 70 the same broadly.

Having thus described my invention, what I claim as new, and desire to secure by Letters Patent, is—

1.. In a fishing-reel frame, the combination 75 of the pillars B, having shoulders at each end; heads A A' consisting of outer and inner metallic plates a a', and intermediate rings a'', perforated to receive said pillars; screws tapped into said pillars at one end, for securing the head A' thereto, and for securing the parts of the said head together; and coupling-pillars B' arranged through said head-plates and rings, threaded to engage the outer plate a of said head A and revolvably secured to 80 said head A', for the purpose specified.

2. In a fishing-reel frame, the combination 85 of the pillars B, having shoulders at each end; heads A A' consisting of outer and inner metallic plates a a', and intermediate rings 90 a'', perforated to receive said pillars; screws tapped into said pillars at one end, for securing the head A' thereto; and coupling-pillars B' arranged through said head-plates and rings, threaded to engage the outer plate a of 95 said head A and revolvably secured to said head A', for the purpose specified.

3. In a fishing-reel frame, the combination 100 of the pillars B, having shoulders at each end; heads perforated to receive said pillars; screws tapped into said pillars at one end for securing one of said heads thereto, the other head being removably arranged thereon; and coupling-pillars B' revolvably secured to said head secured to said pillars B, and threaded 105 to engage the other head, for the purpose specified.

4. In a fishing-reel frame, the combination 110 of the fixed pillars; a head secured thereto; a head removably arranged thereon; and a coupling-pillar revolvably secured to said fixed head and threaded to engage said removable head, for the purpose specified.

5. In a fishing-reel frame, the combination 115 of the fixed pillars; a head secured thereto; a head removably arranged thereon; and a coupling-pillar revolvably connected to said fixed head and detachably connected to said removable head, for the purpose specified.

6. In a fishing-reel frame, the combination 120 of the fixed pillars; heads arranged thereon; and a coupling-pillar revolvably connected to one of said heads and detachably connected to the other, for the purpose specified.

7. In a fishing-reel frame, the combination 125 of the fixed pillars; heads arranged thereon; and a coupling-pillar arranged to secure said heads together, for the purpose specified.

8. In a fishing-reel frame, the combination with the heads, of an adjustable or coupling pillar arranged to detachably connect said heads, whereby said heads may be secured together or released as desired by the manipulation of said pillar, as specified.

In witness whereof I have hereunto set my

hand and seal in the presence of two witnesses.

WILLIAM SHAKESPEARE, JR. [L. S.]
